SCOOP AND DISPENSER DEVICE FOR GAME CHIPS

Judith E. Andamasaris, 718 N. Drive,
New Buffalo, Mich. 49117

Filed Apr. 19, 1971, Ser. No. 135,522

Term of patent 14 years

Int. Cl. D21—01

U.S. Cl. D34—13

Fig.-1

Fig.-2

Fig.-3

Fig.-4

Fig.-5

Fig.-6

FIG. 1 is a side view of the scoop and dispenser device for game chips embodying my design;

FIG. 2 is a front view thereof;

FIG. 3 is another view showing the opposite side of my invention;

FIG. 4 is a rear view;

FIG. 5 is a top view; and

FIG. 6 is a bottom view.

I claim:

The ornamental design for a scoop and dispenser device for game chips, substantially as shown.
